UNITED STATES PATENT OFFICE.

EDGAR BOYD KAY, OF WASHINGTON, DISTRICT OF COLUMBIA.

INCINERATOR.

Application filed June 6, 1924. Serial No. 718,392.

This invention relates to incinerators or other form of furnace and more particularly to a portable type which can be transported in sections and quickly erected.

5 The objects being to provide a construction which may be assembled in units each unit being designated for a certain position in relation to others which may be transported in the said unit form to the site for 10 location and erected quickly by unskilled labor without requiring the services of a bricklayer or a mason.

This and other objects will appear in the following description and be finally pointed 15 out in the appended claims.

Similar numerals indicate corresponding parts in all the figures of the drawings in which:

Fig. 1 is a front elevation of the im- 20 proved portable incinerator.

Fig. 2 is a side elevation.

Fig. 3 is a rear elevation.

Fig. 4 is a vertical section on the line 4—4 of Fig. 6.

25 Fig. 5 is a section on line 5—5 of Fig. 6.

Fig. 6 is a horizontal section on 6—6 of Figs. 2 and 5.

Fig. 7 is a detail of a corner of the base 30 plate.

Fig. 8 is a detail view of a metal frame.

Fig. 9 is a detail of cement slab.

Reference now being had to drawings by numerals, 1 represents a base plate preferably slightly greater than the entire horizontal area of the furnace, on which are mounted angle irons 2 around the outer edge between which a slight space is left for the reception of upright members of the frame.

The sides of the incinerator are constructed of panels, said panels being formed of a metal frame 3 having the vertical side members 4 and the horizontal upper and lower members 5 and 6. Said frame is provided with gusset plates 7, securely bolted at the 45 corners to provide a solid structure.

Said vertical frame members 4 are preferably formed of T-irons adapted to provide a surface against which the slab is mounted both along its outer face as well as its edge 50 and such construction also provides for flanges extending outwardly through which bolts may be passed for securing the panels together.

Mounted in the frames 3 are slabs 8 of re-

fractory and insulating material protected 55 on its outer face with a facing 9 of Russia iron or other material having a finished and anti-rust surface.

Where openings of any character are necessary such as a stoking door 10 or an ash door 11, as seen in Fig. 1, said openings with their closures are formed in a metal plate which is mounted in the frame and secured therein by bolts 12.

As stated above, the several panels with 60 the necessary openings are fabricated at the factory and are transported to the site for erection. The base plate is located and the panels are stepped with their lower edges in the space between the channels 2—2 70 mounted on the base plate and brought up into position and secured by bolts 13. Panels of various widths and provided with openings where necessary, are secured as above described.

75 At the corners are provided Z-irons 14 adapted to be bolted as seen at 15 to the T iron of a panel at the end of the furnace, and project around and is bolted to the outer face of one of the panels at the side or front of the furnace (as seen in Fig. 6) and is bolted at 16.

80 The outer insulating slab 8 is preferably constructed of diatomaceous earthy material and cement having high insulating value and 85 of low specific gravity and also of light weight construction, the combination having approximately the same co-efficient of expansion as that of the metal frame which encloses it.

90 After the outer casing or shell formed by the assembling of the panels referred to are erected, the interior lining constructed of refractory blocks is arranged, each being so indicated as to represent its position and when assembled provide the ash chamber 35 over which the grate supporting channel 36 is located, and on which the grate bars 37, of any preferred construction, rest. Over 95 the grate is the fire chamber 17, to one side of the fire chamber 17 is arranged the drying hearth 18, having a concave upper surface. Leading into the furnace over the drying hearth is the charging opening 19, consisting of the chute preferably of steel plate in which is mounted a vertically slideable guillotine door 20 provided with a counter-weight 21 connected by a flexible cable 100 105 22

over sheaves 23 to facilitate the adjustment of the door 20.

The combustion chamber 24 is separated from the firing chamber 17 by a partition 25 through which a passage 26 leads from directly over the drying hearth through which the products of combustion are drawn from the fire chamber over the drying hearth and out through said opening into the combustion chamber. Leading into the combustion chamber is a clean out door 27 through which the ash in the pit of the combustion chamber may be removed.

Leading from the combustion chamber is the flue 28 in communication with the chimney. A damper 29 constructed of a refractory material mounted preferably in a metal frame 30 is designed to control the draft. Damper 29 is adapted to slide vertically in a guide way 31 in the masonry. Said damper is provided with a counterweight 32 connected by flexible cable 33 over sheaves 34, to facilitate the operation of said damper.

When the interior lining of the furnace is built up a slab of material similar to that used in the outer panels is placed over the top to make a complete closure.

In using this incinerator, material to be destroyed is inserted through charging opening 19 on to the drying hearth 18, where it is first dried and from which position it is stoked over on to the fire grates where it is consumed and the gases of combustion pass out of the fire chamber through the opening 26 over the drying hearth, into the combustion chamber where the final combustion is completed. The position of opening 26 in relation to the fire chamber provides for a swirling and retarding motion of the gases to enable more complete consumption of the gases in the combustion chamber on its way to the chimney.

Having thus described my invention, what I claim as new and desire to secure by Letters Patent is:

1. A portable incinerator comprising a base plate, spaced angle irons mounted on the base plate near its edges, side and end panels stepped in the space between said angle irons and bolted together along their vertical edges, Z irons arranged at the corners and bolted to an end and a side panel, a lining of refractory material and a top slab of refractory material adapted to rest on the lining to form a closure.

2. A portable incinerator comprising a base plate, spaced angle irons mounted on the base plate near its edges, side and end panels consisting of metal frames, slabs of insulating and refractory material mounted in the frames said frames adapted to be stepped in the space between said angle irons, and bolted together along their vertical edges, Z irons arranged at the corners and bolted to an end and a side panel, a lining of refrac-

tory material and a top slab of refractory material adapted to rest on the lining to form a closure.

3. A portable incinerator comprising a base plate, spaced angle irons mounted on the base plate near its edges, side and end panels consisting of metal frames having T iron side members, the stems of said members extending toward each other, a slab of refractory material secured to one face of the stems and to its adjacent flange said frames being stepped in the space between said angle irons, and bolted together along their vertical edges, Z irons arranged at the corners and bolted to an end and a side panel, a lining of refractory material and a top slab of refractory material adapted to rest on the lining to form a closure.

4. A portable incinerator comprising a base plate, spaced angle irons mounted on the base plate near its edges, side and end panels consisting of metal frames having T iron side members, the stems of said members extending toward each other an upper angle iron and a metal strip connecting the lower ends of the side members, a slab of refractory material faced by a metal plate mounted in the frame, and secured to one side of the said stems and to the adjacent inner flanges, said frames being stepped in the space between the angle irons mounted on the base plate and bolted together through their outer flanges, corner members connecting the adjacent edges of side and end panels, a lining of refractory material and a top slab of refractory material adapted to rest on the lining to form a closure.

5. A portable incinerator comprising a base plate, spaced angle irons mounted on the base plate near its edges, side and end panels consisting of metal frames, opening frames mounted in said first mentioned frames, closures mounted on said opening frames, slabs of refractory material carried by said metal frames, said metal frames being stepped in the space between said angle irons, and bolted together along their vertical edges, corner irons connecting the adjacent edges of side and end panels, a lining of refractory material and a slab of refractory material resting on said lining to form a closure.

6. A portable incinerator comprising a base plate, side and end panels mounted on the base plate having outer and inner vertical flanges, slabs of refractory material secured between the inner flanges and means passing through the outer flanges to secure the panels together, corner irons adapted to be secured to the outer flange of one frame and the face of the adjacent frame, a lining of refractory material and a closure slab over the top.

7. A portable incinerator having a base plate, spaced angle irons mounted on the base

plate, side and end panels having the required stoking, ash pit, and flue openings stepped in the space between the said angle irons and bolted together along their vertical edges, a lining and divisional walls of refractory material forming separate chambers inserted from above and a slab of re-

fractory material resting on said lining and divisional walls to form a closure for the separate chambers, openings through said lining to permit access to the interior of said chambers, and means for closing said openings.

EDGAR BOYD KAY.
